SCREEN CHUTE

Archibald L. Smith and Francis E. McGovern,
Columbus, Ohio, assignors to The Jeffrey Manufacturing Company, a corporation of Ohio

Application August 19, 1935, Serial No. 36,817

10 Claims. (Cl. 209—399)

This invention relates to screen chutes, particularly of the type adapted to be employed to screen coal to size as employed in a coal tipple.

An object of the invention is to provide a chute having a screen made up of removable sections which are simple and rugged in construction, which screen sections may be readily removed and replaced by other sections having different size screen openings therein.

Another object of the invention is to provide a chute in which removable screen sections of widely varying lengths may be employed.

Other objects of the invention will appear hereinafter, the novel features and combinations being set forth in the appended claims.

In the accompanying drawings:

Fig. 1 is a side elevational view of a screen chute comprising my invention;

Fig. 2 is an end sectional view taken on the line 2—2 of Fig. 1;

Fig. 3 is an enlarged side view showing the mounting of a screen section;

Fig. 4 is a perspective view of a screen section;

Fig. 5 is a side elevational view of a shaker type of screen chute comprising my invention;

Fig. 6 is an enlarged detail side view of a portion of the chute of Fig. 5 showing particularly the mounting of the screen sections;

Fig. 7 is a sectional end view on the line 30 1—7 of Fig. 6;

Fig. 8 is a side view of a portion of the screen chute showing the construction of a lip type of screen section;

Fig. 9 is a sectional end view of a modified 35 form of screen chute; and

Fig. 10 is an enlarged side view showing a detail of the device of Fig. 9.

Referring particularly to the drawings, there is seen a chute 10 which is adapted to receive 40 material, such as coal, from a conveyor 11, which may be a belt conveyor, the coal being directed to the chute 10 by an auxiliary chute 12. The chute 10 is provided with a screen 13 which may be made up of a plurality of screen sections 14, 45 which screen sections 14 are removably and interchangeably carried in the chute 10.

Adjacent the bottom of the chute 10 may be one or more auxiliary discharge chutes 15 which lead to a guide spout 16. An adjustable gate 50 valve 17 may be provided to direct material which passes through the screen 13 forward of the discharge chute 15 into said discharge chute. It will thus be evident that as coal is fed to the chute 10 the particles thereof, which are able 55 to pass through the apertures of screen 13, may

be directed by the valve 17 into the discharge chute 15 and to the guide spout 16, by which they may be guided into a car in a manner well known to those familiar with tipple practice.

By closing the gate valve 17, the material 5 passing through the screen 13 forward thereof may be passed on down the chute 10 and released with material which passes through the screen 13 below said gate valve 17. In general practice, the screen sections 14 of the screen 13, which 10 are positioned above the gate valve 17, will have relatively small openings therein whereby only relatively fine material will pass therethrough. The screen sections 14, positioned below the gate valve 17, will have larger openings therein 15 whereby larger size coal particles may pass therethrough. Any number of screen sections with different size openings may be provided to screen selectively and progressively the material which passes down said screen 13. 20

One of the principal features of our invention resides in the construction of the screen sections 14 and the co-operating supporting means therefor, whereby said screen sections 14 may be 25 readily removed to the end that screen sections having different size perforations may be substituted therefor, thereby providing a ready control of the size of material received by the chute 15. 30

As best seen in Figs. 1 and 2 of the drawings, 35 the chute 10 comprises the side walls 18, 18 and a closed or imperforate bottom wall 19. The bottom wall 19 is provided with an appropriate opening leading to the auxiliary discharge chute 15, which opening is controlled by the gate valve 17 40 pivoted to shaft 17' and operable by hand lever 18' to open or closed position where it may be locked to brackets 19' or 20', respectively, by a removable bolt and nut. In the closed position, the free edge of valve 17 rests on the ledge 21'. 45

Extending along a straight line longitudinally of the chute 10 and adjacent the side walls 18, 18, there extends a pair of spaced rails 20, 20, which are rigidly attached to said side walls 18, 18 by rivets 21, 21. Appropriate spacers 22, 22 are 50 provided through which the shafts of the rivets 21, 21 extend, whereby the rails 20, 20 will be spaced from said side walls 18, 18 while being held rigidly therewith.

The construction of the screen sections 14 is 55 best seen in Figs. 2, 3 and 4 of the drawings. Said sections comprise a perforate bottom plate 23 having adjacent each side edge a longitudinally and upwardly extending flange 24. Said flanges 24 are provided to lend rigidity to the 55

screen section which is necessary due to the rather severe treatment received by said section as coal moves theracross under the influence of gravity.

Extending transversely of the bottom plate 23 and adjacent each end thereof, there is provided a downwardly extending reinforcing angle member 25 which is positioned on the underside of said bottom plate 23 to lend transverse rigidity to said section.

Adjacent each corner, the bottom plate 23 is provided with a downwardly extending leg 26 which is notched at 27 to receive the spacer 22 about rivet 21. The longitudinal axis of the slot 27 preferably forms a slight angle to the vertical, whereby said axis will be substantially vertical when positioned on the sloping chute 10.

As best seen in Fig. 3 of the drawings, the slot 27 is cut to such a depth that the metal adjacent the bottom portion thereof does not contact with a spacer 22. In other words, the bottom plate 23 will ride on the rails 20 rather than permit the riding of the legs 26 on the spacers 22. This will insure a maximum bearing area for supporting the screen sections 14 and will prevent undue wearing of spacers 22 or slots 27 in legs 26. It will be evident that the function of the slotted legs 26 is to position and hold screen sections 14 in the chute 10.

It is to be noted that the rivets 21 are equally spaced along the chute 10 whereby screen sections 14 of different lengths may be employed in which the distance between the slots 27 is a multiple of the distance between the axes of adjacent rivets 21. That is, a screen section 14 may have any desired length, the only requirement being that the legs 26 be so positioned that the slots 27 are spaced a distance which is a multiple of the distance between the axes of adjacent rivets 21. This permits any screen section 40 to be used in any trough made to these standards.

It is thus evident that a device is provided in which a screen 13 may be made up of a variable number of screen sections 14, which screen sections 14 may be readily removed and replaced 45 either for the purpose of varying the effective size of the openings in the complete screen 13 or for any other purpose.

As is seen from Fig. 1 of the drawings, there is preferably positioned above the opening which leads to auxiliary discharge chute 15 a section of the screen 13 which is not perforated. This section is indicated at 23 and forms a dividing point in the screen 13 between the portion which is adapted to feed the auxiliary discharge chute 15 and the portion which feeds a subsequent, similar chute.

Reviewing briefly the mode of operation of our invention of Fig. 1, coal will be fed to the chute 10 from the conveyor 11. The screen 13 will have sections 14 with relatively small openings therein extending to the plate 28. Relatively fine coal will thus pass through the upper portion of the screen 13 and may be directed by gate valve 17 to the auxiliary discharge chute 15, from which it is received by the guide spout 16 and loaded onto a car. The subsequent screen sections 14 of the screen 13 below the plate 28 may have large size openings to effect a further screening operation on the coal. The size of the openings 70 in the screen 13 may be effectively varied, as desired, by removing the sections 14 and substituting other sections having different size openings in the bottom plates 23 thereof.

In Fig. 5 we have shown a modified form of our invention incorporating a shaking screen 30 hav-

ing a pair of spaced side plates 31 connected together by a transversely extending bottom plate 32 to form a trough. The shaking screen 30 is suspended on framework 33 by appropriate pivoted hangers 34 which allow vibratory movement of said shaking screen 30 with respect to said framework 33. Vibratory movement of said shaking screen 30 is provided by an eccentric mechanism 35 which may be driven from a motor 36 by any appropriate driving means, such as belt 10 37.

A plurality of screen sections 38 is provided which may be of the general structure of the screen sections 14 illustrated in Fig. 4 except for such differences as will be hereinafter specifically 15 pointed out. Said screen sections 38 differ from said screen sections 14 in that in place of the downwardly extending legs we provide downwardly extending pins 39 having frusto-conical 20 points 40.

As best seen in Fig. 5 of the drawings, the axis of the pins 39 make an acute angle with the plane of the screen sections 38 and are preferably substantially vertical. This construction tends to insure against displacement of the screen sections 38 with respect to the shaking screen 30. We also contemplate a structure in which the axis of the pins 39 is at right angles to the plane of the screen section 38.

For supporting the screen sections 38 in the shaking screen 30, we provide a plurality of longitudinally extending angle members 41, one adjacent each side plate 31, the vertical flanges of which are rigidly attached to said plates 31, as by welding. Said angle members 41 are provided 35 with apertures 42 to receive the pins 39. Due to the fact that the pins 39 extend through said apertures at an acute angle to the top web of the angle members 41, the apertures 42 are slightly larger than the pins 39. This construction 40 would result in some looseness of the screen sections 38 on the angle members 41 which would result in undue wear of the pins 39. To provide a closer fit for the pins 39 to prevent relative movement between said screen sections 38 and the shaking screen 30, we provide a plurality of apertured brackets 43, one for each of the pins 39, which are rigidly attached to the angle members 41, as by welding, and which have apertures 44 adapted to provide a relatively close fit with 50 the pins 39.

Where the pins 39 are made perpendicular to the plane of the screen sections 38, the apertures 42 may be made smaller so that said pins 39 fit closely therein, under which conditions the 55 brackets 43 may be eliminated.

It is to be distinctly understood that the construction of the screen sections 38, illustrated in Fig. 5, and the construction of the shaking screen 30, of said Fig. 5, may be employed as a 60 stationary screen, as illustrated in Fig. 1.

It is also to be distinctly understood that the stationary screen of Fig. 1 and the construction of said screen sections 14 of Figs. 1, 2, 3 and 4 may be mounted as a shaking screen, as illustrated in Fig. 5.

In addition to the elements previously described in Fig. 5, we also provide a feed chute 45 for feeding material to the shaking screen 30 and two discharge chutes 46 and 47, respectively, the former of which discharges material from the screen 30 which does not pass through perforations in the screen sections 38 and the latter of which discharges the material which does pass through said perforations.

As illustrated in Fig. 5 of the drawings, the perforated bottom plates of the screen sections 38 are flat. This construction is by no means necessary and in Figs. 6, 7 and 8 we have illustrated bottom plates 48 which extend between a pair of longitudinally extending side straps 48' and are rigidly attached thereto, as by welding. Said bottom plates 48 are also provided with lips 49. This lip construction is sometimes preferred for its aids the movement of the material along the screen. It will, of course, be evident that the screen sections 14 of Fig. 4 may also be provided with a lip type of bottom plate in place of the flat bottom plate 23.

In Figs. 9 and 10, there is illustrated another form of screen chute which may either be the stationary or shaking screen type. This chute comprises side walls 50 and the usual bottom wall similar to bottom wall 19 of Fig. 1 and 32 of Fig. 20, which is not shown.

At spaced intervals along the side walls 50, we provide transversely extending angle members 51 which are welded at their ends to the side walls 50. The top flange 52 of said angle members 51 is provided with spaced perforations 53 adapted to receive the pins 39 of the screen sections 38. It may be noted that, as illustrated in Fig. 10, the pins 39 are perpendicular to the plane of the screen sections 38. When this construction is employed, brackets, similar to the brackets 43 of Figs. 6, 7 and 8, may be omitted.

The angle members 51 have a stiffening effect upon the side walls 50 of the screen which, of course, is not present in the other forms of the 35 invention.

The operation of the device of Fig. 5 is, in general, the same regardless of the exact structure thereof as illustrated by the several modifications in Figs. 6, 7, 8, 9 and 10, and may be briefly described as follows:

Material, such as coal to be sized, is fed to the chute 45. The shaking screen 30 will be oscillated from the eccentric mechanism 35 operated by motor 36. As material is fed to said shaking screen 30, those particles which are smaller than the apertures in the bottom sections of the screen 38 will pass therethrough and flow along the bottom wall 32 of said shaking screen 30 to be discharged by the discharge chute 47. Those material particles which are larger than the apertures in the bottom plates of screen sections 38 will pass over said screen sections 38 and be discharged from chute 46. It will be evident that the screen sections 38 will be rigidly held in place 55 though they may be very readily removed to be replaced by other similar screen sections which may have different size apertures in the bottom plates thereof.

Obviously those skilled in the art may make various changes in the details and arrangement of parts without departing from the spirit and scope of the invention as defined by the claims hereto appended, and we wish therefore not to be restricted to the precise construction herein disclosed.

Having thus described and shown an embodiment of our invention, what we desire to secure by Letters Patent of the United States is:

1. In a chute, the combination with a trough 70 having side walls, of rails positioned adjacent said side walls and extending longitudinally thereof, means for spacing and supporting said rails inwardly of said trough side walls comprising a plurality of equally spaced rivets, and a plurality of separately removable screen sections

of different lengths and interchangeably mounted on said trough, each having upwardly extending side flanges and downwardly extending legs, said legs having notches received by said rivets, said sections having perforated bottoms resting on 5 said rails.

2. In a chute, the combination with a trough having side walls, of rails positioned adjacent said side walls and extending longitudinally thereof, means for spacing and supporting said rails 10 inwardly of said trough side walls comprising a plurality of equally spaced rivets, and a plurality of separately removable screen sections of different length, each having downwardly extending legs, said legs having notches received by said 15 rivets.

3. In a chute, the combination with a trough having side walls, of a rail positioned adjacent a side wall and extending longitudinally thereof, equally spaced rivets passing through said side 20 wall and said rail, spacing means about said rivets between said rail and side wall, and a screen section supported by said rail and having downwardly extending legs notched and receiving said spacing means, said notch being of such depth 25 that the leg portion forming the bottom thereof is out of contact with said spacing means.

4. In a chute, the combination with a trough having side walls, of a rail positioned adjacent a side wall and extending longitudinally thereof, 30 securing means adapted to pass through said side wall and said rail, spacing means about said securing means between said rail and side wall, and a screen section supported by said rail and having downwardly extending legs positioned 35 adjacent said spacing means, said legs being constructed and arranged so as to prevent longitudinal movement of said screen section relative to said trough without carrying the vertical load on said screen.

5. In a chute, the combination with a trough having side walls, of a rail positioned adjacent a side wall and extending longitudinally thereof, equally spaced rivets passing through said side 45 wall and said rail, spacing means about said rivets between said rail and side wall, and a plurality of separately removable screen sections of different lengths supported by said rails and each having downwardly extending legs notched and receiving said spacing means.

6. A screen section for a multiple section screen comprising a perforated metal bottom plate having upwardly extending longitudinal side flanges, and short substantially equi-length downwardly extending legs adjacent each end of said section 55 and along each side thereof, said legs having downwardly opening retaining notches therein adapted to lock said section.

7. A screen section for a multiple section screen comprising a perforated bottom plate having upright longitudinal side flanges, and four downwardly extending retaining legs of substantially equal length, one adjacent each corner of said section.

8. In a screen, the combination with a trough 65 comprising spaced upright longitudinally extending side walls interconnected by a transversely extending member, of longitudinally extending angle members having vertical flanges rigidly attached to said side walls and inwardly 70 extending flanges, a plurality of individually removable screen sections carried on said flanges, said sections each having downwardly projecting pins extending through cooperating apertures in the inwardly extending flanges of said angle 75

members, and angle clips attached to said side walls and having apertures cooperating with said pins to prevent sliding movement between said sections and said trough.

- 5 9. In a chute, the combination with a trough having side walls, of a rail positioned adjacent a side wall and extending longitudinally thereof, spaced rivets passing through said side wall and said rail, spacing means about said rivets between said rail and side wall, and a screen section supported by said rail and having downwardly extending legs notched and receiving said

spacing means, said notch being of such depth that the leg portion forming the bottom thereof is out of contact with said spacing means.

10 10. A screen section comprising a flat perforate metal plate having a flange extending upwardly at each side thereof, a leg extending downwardly from each corner, each leg being formed of a flat plate parallel with said flanges and having a bottom opening notch to hold said section in place.
